UNITED STATES PATENT OFFICE

MORRIS SALINGER, OF NEW YORK, N. Y., ASSIGNOR OF ONE-HALF TO EMANUEL D. STEIN, OF NEW YORK, N. Y.

DESIGN FOR A COMBINED CIGARETTE DISPENSER AND ASH TRAY

Application filed April 30, 1930. Serial No. 35,448. Term of patent 7 years.

To all whom it may concern:

Be it known that I, MORRIS SALINGER, a citizen of the United States, residing at New York city, New York, county of New York, and State of New York, have invented a new, original, and ornamental Design for a Combined Cigarette Dispenser and Ash Tray, of which the following is a specification, reference being had to the accompanying drawings, forming a part thereof.

In the drawings—

I claim:

The ornamental design for a combined cigarette dispenser and ash tray as shown.

MORRIS SALINGER.
